CLAIM

The ornamental design for a rowing machine, as shown and described.

DESCRIPTION

FIG. 1 is a perspective view of a rowing machine showing our new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the encircled portion "9" in FIG. 1;

FIG. 10 is an enlarged view of the encircled portion "10" in FIG. 1;

FIG. 11 is an enlarged view of the encircled portion "11" in FIG. 1;

FIG. 12 is an enlarged view of the encircled portion "12" in FIG. 2;

FIG. 13 is an enlarged view of the encircled portion "13" in FIG. 2;

FIG. 14 is an enlarged view of the encircled portion "14" in FIG. 2; and,

FIG. 15 is an enlarged view of the encircled portion "15" in FIG. 2.

The equal-length broken lines depict portions of the rowing machine that form no part of the claimed design.

The dash-dot broken lines in FIGS. 1, 2, 9, 10, 11, 12, 13, 14 and 15 illustrate the boundaries of the enlarged view indicators and form no part of the claimed design.

1 Claim, 15 Drawing Sheets
